UNITED STATES PATENT OFFICE.

HOWARD A. CHURCH, OF ELKHART, INDIANA.

DESIGN FOR A PITCHER.

Application filed June 24, 1922. Serial No. 2,816. Term of patent 3½ years.

To all whom it may concern:

Be it known that I, HOWARD A. CHURCH, a citizen of the United States, residing in the city of Elkhart, county of Elkhart, Indiana, have invented a new and original and ornamental Design for a Pitcher, of which the following is a specification, reference being had to the accompanying drawing, forming a part hereof.

On the drawing, the single figure is a side elevation which clearly illustrates my design for a pitcher.

I claim:

The ornamental design for a pitcher, as shown.

In witness whereof I have hereunto affixed my signature this 22d day of June, 1922.

HOWARD A. CHURCH.
